CAP-SPINNING APPARATUS

William Harry Kimpton, Spondon, near Derby,
England, assignor to Celanese Corporation of
America, a corporation of Delaware

Application July 2, 1940, Serial No. 343,535
In Great Britain July 19, 1939

5 Claims. (Cl. 57—74)

This invention relates to improvements in or relating to cap spinning apparatus.

According to one important feature of the invention, the throwing-on of the yarn in starting up the cap-spinning operation is facilitated by means of a notched disc resting on and supported by the spindle below the bobbin, the notches running angularly from the periphery of the disc to receive the thread presented to the disc and containing means to grip firmly the thread pulled into a notch. As the thread is thus picked up by the disc rotating with the spindle, it becomes attached to the bobbin to enable winding to start; and the tail of thread extending below the disc is cleanly broken away.

The means for gripping the thread may consist of soft rubber pads confined in recesses in which the notches terminate. Centrifugal force presses the pads outwards in their recesses, so that as the thread is pulled between a pad and the edge of the recess containing the pad it is firmly gripped.

The breaking away of the tail of yarn is particularly important in the cap spinning of threads of artificial filaments, such as cellulose acetate threads, since the high speed at which such threads are usually delivered to the cap spindles in the course of their manufacture makes the manual severance close to the bobbin exceedingly difficult, and long lengths of lashing tails are frequently produced.

The rubber pads may conveniently be held in place in their recesses by means of plates secured to the faces of the disc so as to cover the recesses except for portions near the periphery of the disc sufficient to permit the entry of the thread to be gripped by the pads. The edge of the disc and the tips of the nibs formed by the notches are smoothed so as not to endanger the fingers of the operative. The disc may be recessed so as to engage driving lugs on the spindle.

A further important feature of the invention is concerned with the application of a throwing-on device of the character described above, to the mechanical transfer of thread from a completely wound bobbin on one cap spindle to an empty bobbin on another cap spindle. As completion of one bobbin approaches, an auxiliary balloon guide is brought into position just below the main balloon guide over the spindle on which winding is taking place to permit the auxiliary guide to take over temporary control of the thread. The main balloon guide is then caused to traverse from a position co-axial with the one spindle to a corresponding position at an ad-

jacent spindle, so that the thread follows a horizontal path from the main guide to the advanced auxiliary guide. Between the spindles a vertically-dependant flexible fork is carried by a vertical guide, and is allowed to fall on the horizontal length of thread extending between the two guides, thus forming a thread loop between the two spindles. While winding still continues at the one spindle the loop of thread is carried downwards between the spindles, and as the fork approaches the bobbin rail it encounters a curved surface which deflects it under a notched disc below the bottom flange of the empty bobbin of the adjacent spindle, the thread then being seized by the notched disc. As the notch into which the thread happens to be led grips the thread, the thread is broken below the disc, and the tail of thread is taken up on the completed bobbin. At the same time winding is transferred to the empty bobbin.

The fork then rises on its guide in readiness for a further descent, a switch on the vertical guide for the fork being actuated by a pin on the fork so that the next time the fork descends it encounters an oppositely curved surface near the bobbin rail to deflect the thread under the first spindle, which by this time has had its completed bobbin removed and an empty bobbin placed on it. Before this second transfer of thread from spindle to spindle, a similar operation of auxiliary balloon guide and traverse of the main balloon guide take place. Conveniently the auxiliary balloon guides for the two spindles are actuated by a common lever so that as one guide advances to take control of the thread below the main balloon guide the auxiliary guide recedes.

The flexible fork is conveniently formed of a number of chain links permitting flexibility in either direction from the vertical when the tip of the fork encounters one or other of the curved surfaces.

A timing mechanism operating on a cycle appropriate to the size of bobbin, the weight (denier) of the thread, and the speed of delivery of the thread may be used to effect the mechanical transfer of thread automatically. Advantageously one timing mechanism controls all the spindles of a spinning machine, so that the automatic transfer from one spindle to another takes place simultaneously over the whole length of the machine. The mechanism may be applied either to the automatic operation of existing machines, in which case half the spindles are used for winding, while the remaining half contain empty bobbins

in readiness for the transfer. On the other hand, a machine may be provided with an additional row of spindles, e. g. in front of the existing row, and, if desired, staggered with respect thereto, the forked guides being suitably disposed between a spindle of one row and the corresponding spindle of the other. Again, the additional spindles may be placed in front of and in line with the existing spindles, and a single guide may carry two forks so as to effect the transfer of thread from one pair of spindles to an adjacent pair.

The accompanying diagrammatic drawings show a cap-spinning apparatus in which a double-row of spindles is provided, transfer of thread being between two adjacent spindles of the same row, and each such pair of spindles in each row having its own forked guide.

In the drawings:

Fig. 1 is a front elevation showing the timing mechanism;

Figs. 2 and 3 are a side elevation and a plan of Fig. 1, the timing mechanism being omitted;

Fig. 4 is a plan of a throwing-on disc;

Fig. 5 is a part-sectional elevation of the disc;

Figs. 6, 7 and 8 are front and side elevations and a plan of a detail of Figs. 1 and 2, to a layer scale; and Fig. 9 is a development of the controlling cam shown in Fig. 1.

Referring to Figs. 1-3, cellulose acetate threads produced in the spinning-cell 2 are drawn from the cell by a feed-roller 3 and delivered thereby to two rows of cap-spinning devices 4. To provide for the lubrication of the threads, an oil trough 5 is disposed between the cell 2 and the feed-roller 3 and the threads contact with wick-material 6 depending into the trough. The quantity of oil necessary for efficient cap-spinning and for satisfactory later handling of the yarn is controlled in accordance with such factors as thread denier and spinning speed by suitably adjusting the distance between the level of the oil in the trough 5 and the point of contact of the thread with the wick 6, and by suitable choice of wick, as by using a heavy wick for heavier applications of oil, and lighter lamp wick for lesser applications.

For each thread, a pair of cap-spinning devices 4 is provided, only one such pair being shown in Fig. 1, although it will be readily apparent that such pairs extend to the left along the whole length of the spinning machine, the cap-spindles 7 being carried by the spindle-rail 8. Each feed-roller 3 receives two threads from the cell 2, one thread being delivered to a pair of spindles of an inner row and the other to a pair of spindles of an outer row, the spindle-rails 8 for the two rows being shown in Fig. 2.

The bobbins 9 carried by the bobbin-rails 10 are traversed up and down in the usual way by poker bars 11 operated by suitable cam-gear (not shown), and the four bobbins associated with one feed-roller are driven by a single driving-tape 12, as shown in Fig. 3.

A frame 13 carried by the spindle-rails 8 provides a support for pillars 14, of which one is provided for each pair of bobbins. Each pillar of the inner row carries a guide 15 by which a thread is directed to the outer row of bobbins. Above each pair of bobbins is a main balloon guide 16, these guides being carried by rods 17 slidably lengthwise of the machine so that it may be brought into line with one or other of the bobbins.

Below the level of the guide 16, a pair of substitute balloon guides 18 is provided, one for each bobbin. Front and back guides 18 are carried by rods 19 slidably forwards and backwards so that each guide may be brought into line with its bobbin or retracted. The rods 19 are connected by a lever 20 centrally pivoted at 21 so that when one pair (e. g. left-hand) of guides 18 are retracted, the other pair is in line with its pair of bobbins. With the main guides 16 in line with the left-hand pair of bobbins and the substitute guides 18 retracted from this pair of bobbins, two threads 1 proceed to the left-hand bobbins, one direct from the feed-roller 3 to the inner guide 16 and the other by the guide 15 to the outer guide 16 (see Fig. 2).

Below each bobbin is a throwing-on disc 22 comprising a central plate 23 slightly larger than the bottom flange 24 of the bobbin. The edge of the plate 23 is notched acutely as shown at 25, each notch ending in a circular gap 26 filled by a soft rubber disc 27. The several discs 27 are held in place by outer plates 28 secured to the disc 23 and partially overlapping the recesses 26.

Between each pair of bobbins in both inner and outer rows is a deflector plate 29 that has a peak mid-way between the bobbins and then curves down to each side to pass below the throwing-on discs 22. The plate 29 serves to direct to one or other of the bobbins a flexible mechanical finger 30 movable up and down the pillar 14. The finger consists of three links 31 hinged together at 32, the uppermost link being attached to an arm 33 carried by a stud 34 extending through a vertical slot 35 in one side of the pillar 14 and secured to a weight 36 lying inside the pillar. A spring 37 is connected at 38 to the links 31 to keep them in line, with a guide 39 secured to the lowest link pointing downwards.

A prong 40 extends from the lowest link 31 towards the pillar 14 and just below the level of the prong when the finger 30 is raised to the top of the pillar is a funnel 41 from the throat of which a guide-bar 42 extends towards the level of the bottom flanges of the bobbins at the lowest point in their traverse. A pivot 43 at the top of the bar 42 carries a flap 44, the lower end 45 of which is in the form of a loop free to pass through a slot 46 in the bar 42 and into slots 47 in the sides of the funnel 41, reaching limiting positions in which the upper end of the flap is roughly parallel to one or other of the inclined walls of the funnel.

When the finger 30 is lowered, the flap 44 directs the prong 40 to one side of the bar 42, so that ultimately the guide 39 on the finger 30 meets the corresponding side of the deflector 29. But during the early part of the descent of the finger, the prong 39 engages the loop 45 of the flap 44 and rocks the flap about its pivot 43 until its upper end lies across the path that the descending prong had followed. Then, when the finger 30 is raised, the prong meets the flap, but the flexibility of the finger permits the prong to be diverted until it passes over the top end of the flap to allow the finger to spring back to vertical position. On the next descent of the finger, the flap carries the prong to the other side of the bar 42, and the guide 39 meets the other side of the deflector 29.

This alternating deflection of the guide 39 is used to effect automatic transfer from one bobbin to another, right-to-left, and left-to-right,

in continuous succession, in the following way:

In Fig. 6, the left-hand bobbin 9 is the one on which winding is nearly complete. The substitute guide 18 has been moved forward into line with the bobbin, and the main guide 16 has been moved from the left-hand to the right-hand bobbin, the substitute guide 18 taking over the control of the ballooning thread 1 proceeding to the left-hand bobbin. The movement of the main guide 16 to the right causes a length 48 of thread to run horizontally below the guide 39 and lowering of the guide draws this length into a loop, the left-hand limb 49 of which is kept from contact with the balloon 50 at the left-hand bobbin by a wire guide 51 carried by the guide 18. The right-hand limb 52 of the loop passes over the surface of the cap 53 of the right-hand spindle.

The flap 44 being in the position shown in Fig. 6, the finger 38 is deflected to the right; and the guide 39 contacts with the right-hand side of the deflector 29 to carry the point of the loop 49, 52 under the notched plate 23 of the throwing-on discs rotating with the right-hand bobbin 9. The end of the limb 52 enters one of the notches 25 and is drawn between the rubber pad 27 and the side of the recess 26 into which the notch leads, and centrifugal force causes the pad to grip the limb firmly. The rotation of the disc 23 so tensions the limb 49 that it breaks, the free end of thread being taken up on the left-hand bobbin, and the thread proceeding from the guide 18 begins to wind on the right-hand bobbin.

The weight 36 carrying the finger 38 falls by gravity, as will shortly be described, and it is therefore not necessary for the guide 39 to meet the deflector 29 at any precise point in the traverse stroke of the bobbins, because the guide is deflected as soon as it meets the deflector—which, of course, traverses with the bobbins. When the finger 38 returns to the top of the pillar 14, the flap 44 is set to direct the finger to the left-hand bobbin on its next descent.

Three distinct mechanical movements are required to effect the transfer of the thread:

I. Movement of the pair of main guides 16 from left-to-right or right-to-left. This is effected by coupling the rods 17 by a bar 54 connected by lever 55, link 56, lever 57, and link 58 to a cam-follower lever 59 controlled by a groove 60 of a drum-cam controlling cam 61.

II. Forward and backward movements respectively of the two pairs of substitute guides 18. This is effected by connecting an arm 62 of lever 28 through link 63, lever 64 and link 65 to a 55 cam-follower lever 66 controlled by a groove 67 of the cam 61.

III. Downward and upward movements of the pair of fingers 38. This is effected by cords 68 from the weights 36 passing round and connected to a 60 pair of large-diameter pulleys 69 to which is secured a small-diameter pulley 70. A cord 71 secured to the pulley 70 is connected to a cam-follower lever 72 controlled by a groove 73 of the cam 61.

Although transfer of thread from left-to-right or right-to-left involves similar steps, the full control cycle covers two successive transfers, at the end of which all the parts of the mechanism are in the positions from which they started. The cam 61 therefore makes a half-revolution movement to effect each successive transfer.

The cam 61 is connected by 1:2 gearing 74 to a clutch 75 (of the kind described in U. S. Patent No. 2,176,970) adapted to make engagement with 75

a slow-running shaft 76 when a rod 77 is depressed. Timing-gear 78 of any suitable kind is set to depress the lever 79 pivoted to the top of the rod 77 at intervals of time sufficient to fill a bobbin, the intervals depending on the bobbin size, thread denier, and thread delivery speed. A knob 80 may also be used to depress the rod 77 manually.

When the rod 77 is depressed, the clutch 75 is 10 engaged and makes one revolution before automatically disengaging itself, during which time the cam 61 makes the half-revolution of movement required to transfer the thread from one bobbin to the other, or, rather, from one pair of bobbins to the other pair.

When winding is proceeding on one half of the spindles, the bobbins are doffed from the other spindles and replaced by empty bobbins in readiness for the next transfer. Because transfer is 20 almost instantaneous, the full output of the spinning machine is obtained as wound cap-spun thread—apart from loss due to any accidental thread breakage—and the waste collected during the ordinary manual doffing and donning does 25 not arise. Further, the timing mechanism ensures that the same amount of thread is wound on successive bobbins, and the simultaneous transfer at all the spindles of the machine ensures of course, that all the several bobbins wound 30 at one time contain the same amount of thread.

Having described my invention, what I desire to secure by Letters Patent is:

1. Cap-spinning apparatus comprising a pair of spindles, adapted to support throwing-on devices adapted to receive and grip threads presented thereto, a main balloon guide movable from a position co-axial with one spindle to a corresponding position at the other spindle, means to effect such movement of the main balloon guide, 35 a pair of substitute balloon guides movable into and out of positions co-axial with the two spindles, means for moving one substitute guide into such position at one spindle and the other out of such position at the other spindle, a vertically movable guide disposed between the spindles, means for effecting upward and downward movements of said guide, and means for deflecting said guide towards one spindle on its downward movement to bring into engagement with a throwing-on device at that spindle a thread engaged by the guide between the main balloon guide and one of the substitute guides.

2. Apparatus according to claim 1 wherein the vertically movable guide is flexible so as to be capable of deflection to one side or the other and wherein the deflecting means comprises a plate curving downwardly from its mid-point towards each throwing-on device, one of the curved portions being engaged by the guide on its downward movement to deflect the guide towards the corresponding throwing-on device.

3. Apparatus according to claim 1, wherein the vertically movable guide is flexible, so as to be capable of deflection to one side or the other, and wherein the deflecting means comprises a plate curving downwardly from its mid-point towards each throwing-on device, one of the curved portions being engaged by the guide on its downward movement to deflect the guide towards the corresponding throwing-on device, the apparatus also comprising a member connected to the guide to direct the guide to one curved portion of the deflecting plate and a pivoted flap positioned in the path of said member so as to be moved about its pivot by the member on the downward move-

ment of the guide, so as to direct the guide to the other curved portion of the plate on the next downward movement of the guide.

4. Apparatus according to claim 1 comprising a controlling mechanism for effecting in turn the movement of the two substitute guides, the movement of the main guide from one spindle to the other, and the downward and upward movements of the vertically movable guide.

5. Apparatus according to claim 1, comprising a controlling mechanism for effecting in turn the movement of the two substitute guides, the movement of the main guide from one spindle to the other, and the downward and upward movements of the vertically movable guide, and a timing mechanism for setting the controlling mechanism into operation.

WILLIAM HARRY KIMPTON.
